BASEBALL

Edward W. Kahelin, 812 5th St.,
Manhattan Beach, Calif. 90266

Filed July 12, 1972, Ser. No. 271,022

Term of patent 14 years

Int. Cl. D21—02
U.S. Cl. D34—15 EE

FIG. 1

FIG. 3

FIG. 2

FIG. 4

FIG. 1 is an elevational view of a baseball showing my new design;

FIG. 2 is a top plan view thereof;

FIG. 3 is a right elevational view thereof taken from the right of FIG. 1; and

FIG. 4 is a perspective view thereof taken from the top right of FIG. 2.

I claim:

The ornamental design for a baseball, substantially as shown.
